IMPROVEMENT IN BOXES

Armin Elmendorf, Winnetka, Ill.

Application July 31, 1948, Serial No. 41,873

4 Claims. (Cl. 217—17)

My invention relates to an improvement in containers and in blanks for forming them.

One purpose is to provide an improved blank for the formation of rectangular containers.

Another purpose is to provide an improved blank which includes a wood component and which is nevertheless easily formed into a container without the use of special machinery.

Another purpose is to provide a composite wood board blank with improved bendable or hinged portions.

Another purpose is to provide a composite wood and paper blank in which a plurality of wood veneer strips are employed, separated sufficiently to destroy their original structure, but keeping their relative positions in the blank and in the container formed by the blank.

Another purpose is to provide a blank for rectangular containers which may be stored and shipped flat and which includes securing and reinforcing means adapting it to be assembled, without special tools, into a reinforced and tightly secured container.

Another purpose is to provide a blank for rectangular containers which includes reinforcing cleats of wood or the like.

Another purpose is to provide an improved blank for rectangular containers which includes securing or binding means, such as sheet metal straps.

Other purposes will appear from time to time during the course of the specification and claims.

I illustrate my invention more or less diagrammatically in the accompanying drawings, wherein:

Figure 1 is a perspective view with parts broken away; Figure 2 is a section on an enlarged scale on the line 2—2 of Figure 1;

Figure 3 is a section on an enlarged scale on the line 3—3 of Figure 1;

Figure 4 is a plan view, with parts broken away, of a form from which the container of Figure 1 may be formed;

Figure 5 is a section on an enlarged scale on the line 5—5 of Figure 4;

Figure 6 is a section on the line 6—6 of Figure 4.

Like parts are indicated by like symbols throughout the specification and drawings.

Referring to the drawings, I start with a blank, illustrated in Figure 4, which includes a layer formed of narrow strips 1 of wood veneer. While the formation of the material does not of itself form part of the present invention, it will be understood that I find it advantageous to employ a composite board having two layers 2, 3 which may be made of any suitable flexible material but which I prefer to make of a strong paper having the characteristics of kraft liner board. The layer of veneer strips 1 is adhesively held between the two layers 2 and 3 of paper. The individual strips of the veneer are separated or severed along the grain, the separation being sufficient to destroy the original structure of the wood. However, I find it advantageous to position the individual strips of wood in their original relative position, though separating them by gaps sufficient to extend the across-the-grain length of the wood by a proportion generally of five to fifteen percent. It will be noted that in Figure 4 the entire blank is formed from a sheet of the above described composite board and that the narrow wood strips extend in parallel across the entire blank. It will be understood that, if desired, I may use more than one piece of veneer for a single blank or container.

2

Since the blank is to be formed into a rectangular container, with a bottom, a top and sides, it will be understood that the blank must be bent or folded along the lines of fold or hinge portions which permit at least 5 a 90° bend without destroying or damaging the strength of the material, or even a bend of 180°, in blanks, are to be folded for flat storage. I find it possible to provide efficient hinge portions or bends by providing wide gaps in the wood layer. With reference, for example, 10 to Figures 4 and 5, I illustrate a wide gap 4, the width of which may be of the order or exceeding the thickness of the material, but which, in any event, is sufficient to permit adjacent panels of the blank to be folded 90°, as shown in Figures 2 and 3, or even to be folded 180°. 15 The gaps may be of a width twice the thickness, or more, of the material. Since the composite board of which the blank is formed has an inner and an outer layer of paper or its equivalent, the inner layer may advantageously be folded into the gap 4, as shown at 20 3a in Figures 2 and 3. In this connection, I may find it advantageous to make the inner layer of paper thinner than the outer. This, however, is not necessary and it will be understood that I do not wish to restrict myself to such limitation. But whether or not the inner layer is thinner 25 than the outer, the use of the gap 4 provides ample space for the inner layer 3 to fold into the gap as at 3a and the inwardly folded material tends to strengthen or cushion the corner bend 2a of the outer layer 2. This relationship will be clear from Figure 2. With reference to 30 the blank of Figure 4, I illustrate three of the large gaps 4, formed along the grain of the wood, which define separating hinges between panels A, B, C and D. Each of the large gaps 4 has aligned therewith, at each end, a complete separation 4a between adjacent panels. It 35 will be understood that in the particular form herein shown the panels A, B, C and D may constitute the side walls of the container shown in Figure 1. The panels A, D in the completed container may abut, as shown in Figure 1. Whereas, the wide gaps 4 are along the grain 40 of the veneer strips 1, I employ also a series of wide gaps 5 which extend across the grain. These may, for example, be cut out of the transversely extending strips 1. The wide gaps 4 may also be cut out of the strips, or if desired, some means may be employed, when the material is being manufactured, to effect a periodic, extra spacing between adjacent strips 1. The gaps 5, like the gaps 4, are preferably covered by both layers of paper, 45 as will be clear from Figure 6. The panels F and H, at the top of the container, underlie the panels E and G. The relationship of the opposite row of edge panels I, J, 50 K and L is similar. It will be understood that any suitable reinforcements may be applied along the edges if desired. Some connection is necessary, as at 10, at the junction between 55 the opposed edges of the side wall panels A and D. Similar reinforcements 10a may, if desired, be used at the other corners of the box, although they may, if desired, be dispensed with. Similarly, any suitable securing strips, not herein shown, may be employed to hold the 60 opposed edges of the top panels E and G together or, as shown at 12, to hold the opposed edges of the panels I and K together. It will be realized that whereas I have described and 65 claimed an operative device, many changes may be made in the size, shape, number and disposition of the parts without departing from the spirit of my invention. I therefore wish my description and drawings to be taken as in a broad sense illustrative or diagrammatic, rather than as limiting me to my precise disclosure herein. 70 For example, whereas I find it advantageous to employ a material which includes the inner layer 3 of paper, or a suitable substitute, it will be understood that I may, under some circumstances, prefer to omit the inner layer, where the outer layer 2 is of sufficient strength to form a 75 bend or hinge, or where it is suitably assisted by additional reinforcement. Also, my characteristic hinge formation may be used with composite boards different than the particular one above described. It can be used, for example, in structures other than containers, for example, shipping pallets, where only one right angle bend is 80 required.

As will be observed, for example, in Figure 1, a box made from the blank illustrated in Figure 4 has the advantage that it will include panels the grain of which extends in parallel with each of the three major axes or directions of the box. For example, in Figure 1, the grain is vertical in the side panels A and D and is horizontal in the panels hinged to their upper edges. Of the horizontal panels, the grain in the panels E and G is at right angles to the grain in the panels B and F.

I claim:

1. In a rectangular blank for containers, two layers of generally continuous fibrous material, a layer of wood veneer adhesively secured therebetween, its grain extending from edge to edge of the blank, and gaps in the wood veneer, of a width not less than the thickness of the wood veneer, extending transversely across the blank, approximately parallel with the grain of the wood veneer, said gaps being parallel to each other, the layers of fibrous material bridging said gaps, and constituting integral hinge portions, additional gaps extending along the blank, generally perpendicular to the grain of the wood veneer, and to the transverse gaps in an intersecting relation thereto, said gaps being similarly enclosed by the extension thereacross of the layers of fibrous material, the intersecting gaps together defining a series of aligned, hinged panels extending along the blank, with side panels hinged to the side edges of said aligned panels, the layers of fibrous material being interrupted between the side panels, whereby, when the aligned panels are folded to form sides of a container, side panels are foldable along lines of fold perpendicular to the lines of fold between the aligned panels, to complete the container so formed; the veneer of the blank being separated along the grain into a plurality of closely adjacent but separated wood elements, located in their original position in the veneer, with a separation between adjacent elements of a small fraction of the width of the individual elements, but with the elements sufficiently separated to take up the expansion of the individual elements due to moisture, and thus to prevent cumulative expansion or buckling by moisture of the sides of a container formed by the blank.

2. In a rectangular blank for containers, two layers of generally continuous fibrous material, a layer of wood veneer adhesively secured therebetween, and gaps in the wood veneer of a width not less than the thickness of the wood veneer extending in one direction across the blank, said gaps being parallel to each other, the layers of fibrous material bridging said gaps and constituting integral hinge portions, additional gaps extending generally perpendicular to the first-mentioned gaps in an intersecting relation thereto, said gaps being similarly enclosed by the extension thereacross of the layers of fibrous material, the intersecting gaps together defining a series of aligned, hinged panels to form side walls of a container with wing panels hinged to the side edges of said aligned panels, the layers of fibrous material being interrupted between the wing panels, whereby to constitute said wing panels for use as top and bottom closures of said container, the veneer of the blank having its grain parallel to one set of gaps and being separated along the grain into a plurality of closely adjacent but separated wood elements located in their original position in the veneer with a separation between adjacent elements of a small fraction of the width of the individual elements, but with the elements sufficiently separated to take up the expansion of the individual elements due to moisture, and thus to prevent cumulative expansion or buckling by moisture of the sides of a container formed by the blank.

3. In a rectangular blank for containers, two layers of generally continuous fibrous material, a layer of wood veneer adhesively secured therebetween, and gaps in the wood veneer of a width not less than the thickness of the wood veneer extending in one direction across the

blank, said gaps being parallel to each other, the layers of fibrous material bridging said gaps and constituting integral hinge portions, additional gaps extending generally perpendicular to the first-mentioned gaps in an intersecting relation thereto, said gaps being similarly enclosed by the extension thereacross of the layers of fibrous material, the intersecting gaps together defining a series of aligned, hinged panels to form side walls of a container with wing panels hinged to at least one side edge of said aligned panels, the layers of fibrous material being interrupted between the wing panels, whereby to constitute said wing panels for use as an end closure for said container, the veneer of the blank having its grain parallel to one set of gaps and being separated along the grain into a plurality of closely adjacent but separated wood elements located in their original position in the veneer with a separation between adjacent elements of a small fraction of the width of the individual elements, but with the elements sufficiently separated to take up the expansion of the individual elements due to moisture, and thus to prevent cumulative expansion or buckling by moisture of the sides of a container formed by the blank.

4. In a rectangular blank for containers, two layers of generally continuous fibrous material, a layer of wood veneer adhesively secured therebetween, and gaps in the wood veneer of a width not less than the thickness of the wood veneer extending in one direction across the blank, said gaps being parallel to each other, the layers of fibrous material bridging said gaps and constituting integral hinge portions, additional gaps extending generally perpendicular to the first-mentioned gaps in an intersecting relation thereto, said gaps being similarly enclosed by the extension thereacross of the layers of fibrous material, the intersecting gaps together defining a series of aligned, hinged panels to form side walls of a container with wing panels hinged to at least one side edge of said aligned panels, the layers of fibrous material being interrupted between the wing panels, whereby to constitute said wing panels for use as an end closure for said container, the veneer of the blank having its grain parallel to one set of gaps and at each face layer thereof presenting spaced strips of veneer in original side-by-side relation separated by slits extending generally along the grain and extending inwardly from each face, the width of such slits being a small fraction of the width of the individual strips at each face, but with the strips sufficiently separated to take up the expansion of the individual strips due to moisture and thus to prevent cumulative force leading to expansion or buckling of the sides of the container formed by the blank, the fibrous sheets at each face of the veneer core being effective to rigidify the lined core and overcome the flexibility of the veneer core resulting from the provision of said slits.
